UNITED STATES PATENT OFFICE.

FRANK A. WALTON, OF PORTLAND, OREGON, ASSIGNOR OF ONE-HALF TO FRED W. STEINER, OF SPARKS, NEVADA.

AUTOMATIC TRAIN-STOP.

1,374,342.

Specification of Letters Patent. Patented Apr. 12, 1921.

Application filed September 20, 1920. Serial No. 411,399.

To all whom it may concern:

Be it known that I, FRANK A. WALTON, a citizen of the United States, residing at Portland, in the county of Multnomah and 5 State of Oregon, have invented new and useful Improvements in Automatic Train- Stops, of which the following is a specification.

This invention relates to improvements in 10 automatic train control apparatus and has for an object the provision of means whereby a train approaching a signal set at danger will be automatically stopped.

More specifically stated, the invention 15 aims to provide a normally inactive power and brake operating mechanism which is rendered active by a track device, the latter being controlled by the position of a signal, whereby, when the signal is set for a clear 20 track the train device will remain inactive, and will be operated to cut off the power and apply the brakes of the train when the signal is set at danger.

Other objects and advantages of the invention 25 will appear as the following description is read in connection with the accompanying drawings.

In the drawings:

Figure 1 is a view showing the invention 30 in diagram.

Fig. 2 is an enlarged bottom plan of a locomotive pilot with the train carried device thereon.

Fig. 3 is a side elevation of the same.

35 Fig. 4 is a front view of the subject matter of Fig. 3 with the ramp rails shown in section and the switch in closed position.

Fig. 5 is a fragmentary view showing the switch in open position.

40 Referring to the drawings in detail, wherein like characters of reference denote corresponding parts, the reference character 10 indicates the rails of the track, while 11 includes the pilot of an engine.

45 The track device which is designated in its entirety by the reference character 12 includes a pair of oppositely curved ramp rails 13 which are positioned between the tracks 10 and being spaced apart to provide spaced 50 contact members. The ramp rails 13 are connected in an electric circuit 14 in which is included a circuit breaker 15, the latter being controlled by a rod 16 which is connected to a semaphore arm 17 located beside 55 the track. The semaphore may be the usual

signal employed in connection with the block signal system for the purpose of indicating a clear or occupied block. When the semaphore is set at clear, the circuit breaker 15 is closed, but when set at danger, the circuit breaker will be open so as to interrupt the circuit 14.

The train device which is designated in its entirety by the reference character 18, see Fig. 1, includes an arm 19 which is located 60 within the cab of the engine and is pivotally mounted as shown at 20. The lower end of this arm carries a disk 21 which is notched as indicated at 22, the said notch being normally engaged by one end of a lever 23 which is pivoted at 24 and is held in such engaged position by a spring 25. The opposite end of this arm is in contact with one end of a rigid arm 26, which is mounted as indicated at 27 upon a lever 28, 70 the latter being mounted for pivotal movement upon the pivot 20. The arm 19 carries at its upper end a weight 29 and when the latter descends it will operate a valve 30 included with the air line 31 of the brakes of 80 the train, the stem of this valve forming the pivot 20 of the arm 28, while the arm 19 is secured to the stem.

Connected to the air line 31 is a pipe 32, which is connected to an air cylinder 33, the 85 pipe 32 being controlled by a valve 34 from the stem of which projects an arm 35. The cylinder 33 has operating therein a piston, the rod 36 of which is connected to an arm 37. This arm is pivotally mounted as indicated at 38 and arranged concentrically with this pivot is a segmental gear 39, which operates a gear 40. This last mentioned gear is secured upon the stem 41 of a valve 42 which controls the admission of steam to 90 the engine cylinders 43, steam being conveyed to these cylinders by means of a pipe 44 which leads from the engine boiler. Air passes through the valve 30 from the air pressure tank (not shown) through the pipe 100 45, while stops 46 act to limit the movement of the arm 19 in one direction.

Connected to one end of the arm 28 as indicated at 47, is the armature 48 of an electromagnet 49, the latter being included in 105 a circuit in which is also included a battery 50 or other source of energy. The magnet 49 is connected to the battery by a conductor 51, the latter including stationary contact member 52. Tapped on to the conductor 51 110

is a conductor 53, which connects with an electric magnet 54 which is normally energized. The armature 55 of this magnet carries a movable contact member 56 which, 5 when the magnet 54 is deenergized engages the stationary contact 52 under the action of a spring 57. The magnet 54 is connected by means of a conductor 58 with one terminal 59 of a switch 60 which is mounted upon the 10 pilot 11 of the engine. The other terminal 61 of the switch 60 is connected by means of a conductor 62 to the opposite side of the battery 50, a conductor 63 tapped on to the conductor 62 connecting with the electro- 15 magnet 49.

The switch 60 which is of novel construction see Figs. 4 and 5 includes a pair of spaced pivoted arms 64 and 65, the free ends of each of these arms being provided with a 20 copper shoe 66. The arm 64 has connected thereto one end of a bar 67, the opposite end of which is adapted to engage the walls of a socket 68 provided in the arm 65. The arms are normally maintained in position to hold 25 the rod 67 within the socket 68 by means of springs 69.

In the operation of the invention, a train approaching a signal will have the shoe 66 of the switch 60 separated through engagement with the curved ramp rails 13. Current which has been normally flowing through this switch, will then flow from the battery 50 through the conductor 62 to the terminal 61, through the shoe 66, one of the 30 ramp rails 13, the conductor 14 and through the circuit breaker 15, the latter being closed when the signal is set for a clear track. The current then flows through the other ramp rail 13, the shoe 66 which engages it, the 35 conductor 58, and the electromagnet 54, so that this magnet remains energized the armature being held in position to prevent engagement of the contacts 52 and 56, current flowing back to the opposite side of the battery 40 through the conductor 50. Should however, the signal be set at danger and the circuit breaker 15 opened to interrupt the flow of current through the conductor 14, the electromagnet 54 will be deenergized and 45 engagement effected between the contacts 52 and 56. The member 56 which having closed the circuit through the conductor 51, the current flows from the battery through the conductor 51, the electromagnet 49 and 50 back to the battery through the conductor 63. The magnet 49 is thus energized and its

armature attracted, whereupon the arm 28 will be pivotally moved to release the disk 21 by disengaging the lever 23, whereupon the weight 29 will carry the arm downward 60 to operate the valve 30 and apply the brakes. During this downward movement, the switch 29 will engage the arm 35 of the valve 34 and admit air to the cylinder 33 for the operation of the piston therein. This will 65 move the piston rod in the direction of the arrow and cut off the supply of steam to the cylinders 43 by closing the valve 42. The parts may be turned to their normal position through the manual operation of the valves. 70

The invention is susceptible of various changes in its form, proportions and minor details of construction and the right is herein reserved to make such changes as properly fall within the scope of the app- 75 pended claims.

Having described the invention what is claimed is:—

1. The combination with a train control apparatus comprising spaced pivotally 80 mounted contact arms, a bar normally connecting said arms and stationary means located in the path of the switch for engagement with the contact arms to operate the latter and disengage the connecting rod to 85 open the switch.

2. The combination with a train control apparatus including a normally closed circuit and means rendered active upon opening the circuit for controlling the operation 90 of the train, of a switch included in the circuit and carried by the train, said switch comprising relatively movable contact members and means located in the path of said members for operating the same to open the 95 circuit.

3. The combination with a train control apparatus including a normally closed circuit and means rendered active upon opening the circuit for controlling the operation 100 of a train, of a switch included in the circuit and carried by the train, said switch comprising yieldingly mounted pivoted contact arms carried by the train, a bar carried by one arm and engageable with the other 105 arm to hold said arms in spaced relation, to bridge the space between the arms, and means located in the path of the arms for separating the latter to interrupt the circuit.

In testimony whereof I affix my signature. 110

FRANK A. WALTON.
